HAIR COMBING, CLIPPING, AND SHAVING
HEAD

Mathew Andis, Racine, Wis.

Application March 5, 1936, Serial No. 67,195

17 Claims. (Cl. 30—43)

My invention relates to improvements in hair combing, clipping, and shaving heads.

In a companion application bearing even date herewith Serial No. 67,196, filed March 5, 1936, for improvements in Hair clipping and shaving heads and which issued as Patent Number 2,141,895 on December 27, 1938, I have illustrated a clipping and shaving head devoid of ordinary comb teeth, and in which the function of lifting 5 and straightening the hair is in part performed by a scraping bar which is reciprocated over the skin to push recumbent hair to or toward a perpendicular position, provision being made for entry of the hair between the shearing teeth at 10 points not occupied by the vibratory cutter, and the entire operating face of the head being cylindrical in form.

A primary object of the invention herein disclosed is to provide a shearing head of the general type disclosed in said companion application with true comb teeth which may be utilized in association with shearing bars of the arcuate type disclosed in said companion application.

Further objects are to provide a shearing head 25 having a cylindrical bearing surface with arcuate teeth which are adapted to operate as comb teeth, with the ends of the teeth passing underneath and lifting the hair while the cylindrical bearing surface is in reciprocatory motion.

30 A further object is to provide convergent shearing teeth which may also perform the functions of comb teeth in a head having a cylindrically curved bearing surface.

A further object is to provide a cylindrically curved shearing head having a correspondingly curved vibratory cutter bar therein and means for contracting the shearing head upon the cutter bar to ensure shearing contact and take up wear.

40 In the drawing:

Figure 1 is a side elevation of clipping and shaving mechanism in which one embodiment of my invention has been incorporated.

Figure 2 is a plan view of the head with a portion of the shearing member broken away.

45 Figure 3 is a section view drawn to line 3—3 of Figure 2.

Figure 4 is a view similar to Figure 3 but showing a modification.

50 Like parts are identified by the same reference characters throughout the several views.

In Letters Patent for Hair clippers and shaving clippers No. 2,037,957, granted to me April 21, 1936, pursuant to a companion application Serial No. 581,634, I have illustrated a tubular

vibratory clipper mounted within a shear plate having forwardly projecting comb teeth, said shear plate being adapted for substantially flat bearing contact with the scalp.

In the improved shearing head disclosed in 5 Figures 1, 2, and 3, the rear portions 12 of the shearing member are provided with rearwardly projecting shanks 13 to facilitate attaching the clipper head to the upper and lower halves 14 and 15 of a suitable casing or handle, which 10 may be assumed to contain power driving means such as an electrical motor or driving connections associated with an external source of power supply.

The forward or working portions of the shearing head are cylindrically curved and include convergent shearing bars 18 and 19, separated by a transversely extending bar 20 similar to the comb bar described in the companion application bearing even date herewith. Adjacent the 20 bar 20 the outer and inner surfaces of the shearing bars 18 and 19 are concentric, but in the laterally extending portions of these bars the outer surfaces diverge from the inner surface to form comb teeth having points 21. At the rear 25 of the points 21 the outer surfaces of these teeth are preferably concavely rounded as indicated at 22. These concave parts are supported from the rear portions 12.

The shear bar is provided with a cylindrical 30 bore to receive a vibratory cutter member. In Figure 3 this cutter member has a cylindrically rounded rear portion 27 and a cylindrically rounded forward portion of reduced arcuate dimensions, provided with arcuate channels 28 and 35 intervening cutter ribs 29 adapted for cooperation with the shearing teeth 18 and 19 when the cutter bar is axially vibrated.

The front and rear portions of the cutter bar are connected with each other by an intermediate web 32, which may have open ended slots 33 and 34 extending inwardly from opposite ends and adapted to allow the front and rear portions of the cutter bar to be pressed toward each other, the material being sufficiently resilient for 45 this purpose. The cutter bar may, therefore, be made slightly larger than the shear bar bore which receives it, and the cutter bar may be inserted while under compression.

In operation, the cutter head may be reciprocated upon the scalp with a rocking motion across a central plane, which includes the shanks 13 and the bar 20. In this reciprocating and rocking motion the points 21 of the comb teeth will engage underneath hair and lift it into the 55

channel-like spaces 35 of the vibratory cutter bar, and thence between the shearing portions of the cutter bar teeth and the shearing bars 18 and 19. During these reciprocal movements 5 of the cutter head the bar 20 will engage and swing toward a position perpendicular to the scalp, hair which has been cut in the previous reciprocal movements, and thus bring the ends into contact with the shearing teeth if 10 such hair is longer than the thickness of the bar 20 and of the associated shearing teeth. This cutter head may be pressed against the skin or scalp to place it under tension, and as the working portions may be made extremely thin, the 15 surface may be shaved with approximately the same close-cutting effect as that ordinarily obtained in the use of a razor when a so-called "close shave" is not required. If desired, the edges of the bar 20 may be made sharp enough 20 to serve as shaving edges.

In Figure 4 I have illustrated a modification in which the body portion of the shearing member is formed in two parts 12a and 12a', each having projecting shanks 13a and 13a', connected by 25 bolts or screws 37, with an intervening filler block 38 to hold the upper and lower halves of the body together. Each of the body portions 12a and 12a' has upper and lower shearing bars 18a and 19a which converge to a longitudinally extending slot or channel 39, which occupies the 30 space corresponding with that occupied by the bar 20 in Figure 3.

The head shown in Figure 4 also has a longitudinally extending bore, within which a cutter bar in the form of a split cylinder is mounted. 35 The rear portion 40 of this cutter bar may be continuous and the forward portion arcuately slotted to provide cutter teeth 41 and 42, positioned for shearing cooperation with the shearing teeth 18a and 19a, and with their convergent ends 40 separated from each other along the line of the slot or channel 39. The ends of the teeth 41 and 42 are preferably separated from each other at a slightly greater distance than the ends of the 45 teeth 18a and 19a.

With the construction disclosed in Figure 4 the cutter head may be manipulated in the manner above described with reference to Figures 1, 2, and 3, but the movement of the comb teeth 50 underneath the hair will take place along the line of the slot or channel 39, and the hair will pass between the ends of the cutter teeth 41 and 42 along this line.

But with the form of construction shown in 55 Figure 4 it is not necessary to compress the vibratory cutter bar preparatory to insertion in the shear bar bore, for the reason that the upper and lower halves of the shear bar are independently formed, and therefore their pressure upon 60 the cutter bar may be determined by the clamping screws 37. To take up for wear, thinner filler blocks 38 are substituted, or if desired, the filler block 38 may be covered with compressible material 45, the resilient reaction of which will tend 65 to predetermine the pressure of the shear bar upon the cutter bar to a sufficient extent to prevent the development of excessive friction.

I claim:

1. In a mechanism of the described class, the 70 combination with a generally cylindrical vibratory cutter bar having channel-like openings for entry of hair flanked by arcuate cutter teeth positioned to receive between them hair which has entered such openings, of a shear bar substantially enclosing the cutter bar and provided with

arcuate teeth for shearing registry with the teeth of the cutter bar, said shear bar teeth having laterally projecting end portions concavo-convex in form and adapted to pass underneath and lift hair preparatory to the cutting operation. 5

2. In a mechanism of the described class, the combination of a vibratory cutter bar of a generally cylindrical form, having one portion arcuately channelled to provide cutter teeth and another portion longitudinally recessed along the 10 ends of such teeth, and an enclosing shear bar having arcuate teeth covering one extremity of each cutter bar tooth and extending over said recess sufficiently to allow hair to enter the recess when the shear bar is being moved with a 15 combing action, said shear bar having longitudinally extending continuous walls supporting the respective ends of the shearing teeth.

3. In a mechanism of the described class, the combination of a vibratory cutter bar of a generally cylindrical form, having one portion arcuately channelled to provide cutter teeth and another portion longitudinally recessed along the 20 ends of such teeth, and an enclosing shear bar having a set of arcuate teeth covering the portions of the cutter bar teeth along said recess and extending over said recess sufficiently to allow hair to enter the recess when the shear bar is being moved with a combing action, said shear bar having longitudinally extending continuous walls 25 supporting the respective ends of the shearing teeth, one of said walls registering with portions of the cutter bar teeth and serving as a combing web, cooperative with the shear bar teeth to predetermine the minimum distance from the 30 scalp at which shearing operations take place.

4. In a mechanism of the described class, the combination of a shear bar having a longitudinally extending cylindrical bore and a thin walled working portion covering said bore at one side, 40 said working portion comprising a longitudinally extending web flanked by arcuately slotted portions providing arcuately curved shearing teeth, a cutter bar in said bore having an arcuate working portion in registry with said web and portions 45 of the teeth at each side thereof, said cutter bar working portion being arcuately channelled to provide cutter teeth, the end portions of which are adapted to move with a shearing action across those portions of the shear bar teeth nearest the 50 web, said cutter bar being otherwise spaced from the wall of the shear bar bore to allow hair to freely pass between the ends of shear bar teeth in registry with such spaces when the shear bar is moved with a combing action along the scalp. 55

5. In a mechanism of the described class, the combination of a shear bar having a longitudinally extending cylindrical bore and a thin walled working portion covering said bore at one side, 60 said working portion comprising a longitudinally extending web flanked by arcuately slotted portions providing arcuately curved shearing teeth, a cutter bar in said bore having an arcuate working portion in registry with said web and portions 65 of the teeth at each side thereof, said cutter bar working portion being arcuately channelled to provide cutter teeth, the end portions of which are adapted to move with a shearing action across those portions of the shear bar teeth nearest the 70 web, said cutter bar being otherwise spaced from the wall of the shear bar bore to allow hair to freely pass between the ends of shear bar teeth in registry with such spaces when the shear bar is moved with a combing action along the scalp, the 75 middle portions of the outer surfaces of the shear

bar teeth being extended laterally for combing purposes.

6. In a mechanism of the described class, the combination with a hollow shear bar and a vibratory cutter bar located therein and provided with means for vibrating it longitudinally, of a longitudinally extending combing web carried by the shear bar, shear teeth extending arcuately from the respective sides of said web and 10 having connected ends supported thereby, said shear bar including supporting means for the ends of the teeth most distant from said web, and arcuate cutter teeth bearing upon the inner surface of said web and the adjacent ends of its 15 associated shear teeth, said cutter bar having other portions spaced from the shear bar and adapted to allow hair to freely enter such spaces between the portions of the shear bar teeth most distant from said web.

20 7. In a mechanism of the described class, the combination of a shear bar provided with a longitudinally extending bore, a vibratory cutter bar mounted in said bore and provided with an arcuate working portion fitted to the wall of said 25 bore along one side, and including a longitudinally extending row of arcuate cutter teeth, said shear bar being arcuately slotted to provide shear teeth supported at both ends and in partial registry with said cutter teeth, said cutter bar having a longitudinally extended channel in registry 30 with the other end portions of the shear bar teeth, whereby, when the shear bar is moved along the scalp with a combing action, hair may enter said channel preparatory to its entry between the teeth of the cutter bar.

8. In a mechanism of the described class, the combination of a shear bar provided with a longitudinally extending bore, a vibratory cutter bar mounted in said bore and provided with an arcuate working portion fitted to the wall of said bore along one side, and including a longitudinally extending row of arcuate cutter teeth, said shear bar being arcuately channelled to provide shear teeth supported at both ends and in partial 40 registry with said cutter teeth, said cutter bar having a longitudinally extended channel in registry with the other end portions of the shear bar teeth, whereby, when the shear bar is moved along the scalp with a combing action, hair may enter said channel preparatory to its entry between the teeth of the cutter bar, and said shear teeth having outer surfaces intermediately extended to provide combing projections between the portions in registry with the cutter bar teeth 45 and the portions in registry with said channel.

9. The combination with a shear bar having a longitudinal bore and a thin working portion on one side, cylindrically curved for bearing contact with the scalp and transversely slotted to provide 50 arcuate shearing teeth on each side of the longitudinal center line of said bearing portion, and a cutter bar having arcuate cutter teeth for registry with the center of the bearing portion of the shearing bar and adjacent portions of the shear bar teeth, the cutter bar being spaced from the shear bar beyond the ends of the cutter bar teeth to allow hair to enter said space from between the shear bar teeth preparatory to being carried with a combing action between the shearing 55 portions of the teeth on the respective bars.

10. In a hair clipping and shaving head, a vibratory cutter bar having a working portion extending longitudinally along one side, and a supporting portion at the other side, connected with 60 the working portion across the central axis of

the bar, said working portion having arcuate channels and intervening arcuate teeth, between which hair may enter from the side of the connecting central portion, in combination with a shear bar having concentric arcuate teeth extending beyond the ends of the teeth of the cutter bar, said ends being provided with combing portions adapted to direct hair into the spaces at the sides of the central portion of the cutter bar to be engaged by the cutter teeth when moving 10 longitudinally through such hair with a combing action.

11. In a mechanism of the described class, the combination of concentric cylindrically curved shearing members, having working portions in 15 resilient pressure relation to each other, the working portion of the outer member comprising a central web flanked by rows of arcuate teeth supported at both ends by the web and the rear portions of said member, respectively, and with 20 portions of the outer member teeth most distant from the web spaced from the inner member.

12. In a mechanism of the described class, a shear bar having all skin contacting portions cylindrically curved and provided with arcuate 25 shearing teeth at opposite sides of a longitudinally extending zone intermediate of said teeth, said zone being occupied by a thin continuous web connecting the opposing ends of the respective sets of teeth, and a cutter bar with which 30 said web and the adjacent portions of the teeth are concentric, said cutter bar being spaced from the other end portions of said teeth to facilitate entry of hair between the shear bar teeth.

13. In a mechanism of the described class, a cutter bar having a longitudinally extending row of arcuate shear teeth along its working front side and a corresponding operating piece along its rear side, the central portions of the rear side and working side being connected by a relatively 40 thin web, said bar being of a generally T-shaped form in cross section.

14. In a mechanism of the described class, the combination of a non-vibratory hollow shear bar having a cylindrically rounded working portion 45 for bearing contact with the skin and provided with sets of arcuate shearing members on opposite sides of the longitudinal center line of said bearing portion, and a vibratory cutter bar having a working portion provided with arcuate 50 shearing teeth in shearing relation to the shearing members of the shear bar adjacent said center line of its working portion, said cutter bar being spaced from the arcuate members of the shearing bar beyond the ends of the cutter bar 55 teeth to allow hair to freely enter between portions of the shear bar members extending beyond the ends of the cutter bar teeth.

15. The combination of a vibratory cutter bar having longitudinally extending channels along 60 opposite sides thereof and also having an arcuate working portion channelled to provide arcuate shearing teeth, an enclosing shear bar having a thin working portion concentric with the arcuate shearing teeth of the cutter bar, and having 65 arcuate slots on opposite sides of the longitudinally extending center line of the working portion, which slots extend beyond the shearing teeth of the cutter bar into registry with the cutter bar channels, whereby the portions between the shear bar slots may serve as combing and shearing teeth with the combing portions adapted to guide hair into the cutter bar channels.

16. The combination with a vibratory cutter 70

bar having oppositely disposed portions provided with cylindrically curved outer surfaces and oppositely disposed longitudinal channels separating said surfaces, one of said surfaces being arcuately channeled to provide shearing teeth and the other being notched to receive an actuating arm for vibrating the bar longitudinally, an enclosing shear bar having a thin wall concentric with the toothed portion of the cutter bar and provided with spaced sets of arcuate slots and shearing teeth, portions of which teeth are in shearing relation to the cutter bar teeth, with other portions overhanging the channels in the cutter bar.

17. The combination of a vibratory cutter bar having along one side a set of arcuately curved shearing teeth and having its opposite side provided with means for vibrating said bar axially, an enclosing shear bar having a thin cylindrically curved bearing portion concentric with the teeth of the cutter bar and arcuately slotted to provide plural longitudinally extending sets of shearing teeth in shearing relation to the respective ends of the cutter bar teeth, said shear bar teeth extending beyond the ends of the cutter bar teeth and spaced from the cutter bar in their outer end portions. 10
